MANIPULATOR UNIT FOR PROGRAMMING MACHINING OPERATIONS

Anthony J. Kaye, Schenectady, N.Y., assignor to American Machine & Foundry Company, a corporation of New Jersey

Filed June 17, 1963, Ser. No. 75,354

Term of patent 14 years

(Cl. D55—1)

FIG. 1

FIG. 2

FIG. 1 is a perspective view of a manipulator unit for programming machining operations showing my new design;

FIG. 2 is a perspective view taken from the opposite side of FIG. 1;

The dominant features of my design reside in the portions shown in full lines.

The undisclosed front inclined portion of the housing is plain and flat.

I claim:

The ornamental design for a manipulator unit for programming machining operations, as shown and described.
